ELLIPSOGRAPH INSTRUMENT

Sifton Friedman, Lynbrook, N. Y.

Application March 29, 1952, Serial No. 279,283

4 Claims. (Cl. 33—30)

1

This invention relates to ellipsographs and is more particularly concerned with an improved construction thereof incorporating means for maintaining a predetermined relation between the element which defines the ellipse and the outline portion of the ellipse being formed.

A principal object of this invention is to provide an ellipsograph capable of describing an ellipse having major and minor axes of any desired ratio including such wherein the major axis is greater in length than twice that of the minor axis, with means whereby the operating element, in the form of either a drawing or cutting member, is maintained in a predetermined relation to the portion of the ellipse being formed.

Other objects of the present invention will be apparent from the following description, it being understood that the present invention consists substantially in the combination, construction, location and relative arrangement of parts, as described in detail hereinafter, as shown in the accompanying drawings and as finally pointed out in the appended claims.

In the accompanying drawings:

Figure 1 is a perspective view of an ellipsograph embodying the present invention; and

Figure 2 is a diagram illustrating the operation of the apparatus shown in Figure 1.

Now referring particularly to the drawing, it will be seen that the ellipsograph of the present invention essentially comprises a standard 10, a beam 11 extending outwardly therefrom, driven and guiding assemblies each carried by the beam 11 and gear means operatively connecting the driven assembly with the standard 10.

The standard 10 is in the form of an elongated upright member having a round transverse cross section and having a base including downwardly diverging parts 12—12 and a horizontal part 13 joining the lower extremities of parts 12—12. The part 13 is apertured to slidably receive a set of three centering pins 14 which are disposed thereby in parallel spaced relation to one another and in a common plane, the intermediate pin 14 being coaxially related to the standard 10. The pins 14 are adjustably secured in working position by thumb screws 16 which are received by tapped openings in the part 13 and which are horizontally disposed thereby for engagement with pins 14.

The beam 11 which extends outwardly from the standard 10 is an elongated member, preferably formed of sheet material having a transverse cross section in the form of a channel provided with a vertically disposed main body portion 17

2

and upper and lower horizontally disposed parallel flanges 18—18. It will be understood, however, that the beam 11 may be of any suitable form other than that shown. For securing the inner end of beam 11 to the standard 10, the former is suitably provided with a laterally extending bracket in the form of a U-shaped member having a vertically disposed main body part 19 and upper and lower horizontally disposed parallel arms 21—21. The bracket is suitably rigidly secured by one edge of its body part 19 to the back of the web part 17 and is positioned thereby in longitudinal continuation of the beam 11 with said body part 19 disposed in a vertical plane normal to the web part 17 and with the arms 21—21 respectively in coplanar relation to flanges 18—18. The opposite end portions of the bracket are apertured to suitably receive vertically spaced portions of standard 10 for rotation 15 of the bracket and the beam 11 thereabout as a unit. The upper longitudinal edge of beam 11 is suitably graduated as at 20 for a purpose to be described hereinafter.

The driven and guiding assemblies which are carried by the beam 11 include slidable brackets 22 and 23 which are respectively provided with upper and lower horizontally disposed parallel flanges 24—24 and 26—26. These brackets 22—23 are arranged to embrace spaced portions of the beam 11 and are mounted for shifting movement therealong, each being secured in predeterminedly selected operative position by a thumb screw 27 which is received by a tapped opening in the upper flange of the bracket for engagement with the upper flange 18 of the main beam 11.

Secured respectively to the slidable brackets 22—23 are a pair of members 28 and 29, said members being in turn respectively provided with upper and lower horizontally disposed parallel flanges 31—31 and 32—32. The members 28 and 29 are suitably rigidly secured back to back respectively to the slidable brackets 22 and 23 with the flanges 31—31 and 32—32 extending frontally of the main body portion 19 of the beam 11.

As clearly appears in Figure 1, opposed portions of the flanges 31—31 are apertured to rotatably receive a vertically extending shaft 33, the upper end portion of which mounts an upwardly presenting bevel gear 35 suitably fixed thereon and disposed just above the upper flange 31. Slidably mounted upon the lower end portion of the shaft 33 is a horizontally disposed arm 34 secured to the shaft in adjusted position by a pair of threaded nuts 36 and 37. The arm 34 is in the form of a flat member having formed therein an

elongated slot 38 through which the lower end of shaft 33 is projected, the slotted arm being locked in adjusted position relatively to the shaft 33 by clamping action of the nuts 36-37. The forward end of the arm 34 is downwardly and rearwardly turned to provide a vertically offset flanged part 39 which is apertured in registry with an aperture in the main body portion of the arm for receiving vertically spaced portions of the shank 41 of a marking element in the form of a drawing pen 42, the latter being thus positioned in depending relation with respect to the arm 34 for oscillation freely about the axis of its shank 41.

With respect to the slidable guide member 23, opposed portions of flanges 32-32 are apertured to oscillatably receive a shaft 43 having a head 44 formed on the upper end thereof for engagement with the uppermost flange 32. The lower end portion of the shaft 43 is apertured for slidably receiving a rod 46 which is provided at one end thereof with an internally threaded ferrule 46a adapted to threadedly receive the shank of the thumb screw 47 of the drawing pen 42.

The gear means operatively connecting the 25 driven assembly with the vertical post or standard 10 includes an upwardly presenting bevel gear 48 suitably secured to the post in axially fixed position thereon. Extending in parallel spaced relation to the beam 11 is a square shaft 49, the opposite ends of which are respectively journaled for rotation in coaxially aligned openings formed respectively in the part 19 at one end of the beam 11 and in a flange 51 at the opposite end of the beam disposed in parallel relation to the part 19. The inner end of shaft 49 projects through the part 19 and mounts a bevel gear 52 for mesh engagement with the bevel gear 48.

Splined to a portion of shaft 49 intermediate its end is a bevel gear 53 which meshes with the bevel gear 35, the gear 53 being thus not only rotatable with the shaft 49 upon rotation of the bevel gear 52, but also shiftable axially of said shaft into any adjusted position therealong. For securing the gear 53 in its adjusted position along the shaft 49, the slidable bracket 22 is offset, as at 54, and slotted, as at 56. The offset section 54 is formed by bending an intermediate portion of the body portion of the bracket 22 outwardly of its plane to provide a rearwardly presenting channel which straddles the shaft 49 and serves as a hand-hold for shifting the bracket 22 into adjusted position along the beam 11 upon which it is slidably mounted. The opposite marginal edges of the slot 56 respectively engage opposite ends of the bevel gear 53 splined to the shaft 49, from which it will be apparent that as the bracket 22 is shifted longitudinally along the beam 11 in any adjusted position thereon, the assembly which includes the interengaging bevel gears 53 and 35, the vertical shaft 33, the arm 34 and the drawing pen 42 is correspondingly shifted into adjusted position.

It will be noted that the bracket 23 which carries the rod 43 is independently adjustable along the beam 11, this latter adjustment being effected upon adjustment of the bracket 22 to properly locate the rod 43 relatively to the shaft 33 as will appear more fully hereinafter. If desired, suitable arrangement may be provided for automatically effecting simultaneous adjustment of the brackets 22 and 23 along the beam 11 so as to properly position them relatively to each for any adjusted position of the shaft 33 toward or away from the post or standard 10.

The standard 10 and all of the shafts 33, 43 and 49 are disposed in a common vertical plane, it being noted also that all of the bevel gears 35, 52 and 53 have the same number of teeth, which number is just half that of number of teeth on the gear 48, in consequence of which the shaft 33 makes two revolutions about its own axis for each complete revolution of the beam 11 about the axis of the standard 10.

In the operation of the ellipsograph of the present invention, the major and minor axes of the desired ellipse, designated respectively by the letters X-X and Y-Y, are preliminarily laid out as desired by the operator. Then the ellipsograph is adjusted for use by shifting the bracket 22 along the beam 11 and securing it in a position wherein the distance between the intermediate centering pin 14, i. e., the axis of the standard 10, and the axis of the shaft 33 is equal to one half the sum of the semi-axes of the ellipse to be drawn. With the shaft 33 thus adjusted, and with the beam 11 swung into position paralleling the horizontal part 13 of the standard 10 at the same time that the arm 34 is rotated into position paralleling the beam so that the beam 11, the arm 34 and the aforesaid part 13 are all parallel, horizontally extending arm 34 is then secured in such radially adjusted position relatively to the axis of the shaft 33 that the distance between the intermediate centering pin 14 and the point of the scribing instrument 42 is equal to one-half the length of the major axis of the desired ellipse. In this last adjusted position of the arm 34, the point of the instrument 42 will be spaced from the shaft 33 a distance equal to half the difference between the semi-major and semi-minor axes. If desired, the beam 11 may be provided with a suitably graduated scale as shown which may be employed in conjunction with a pre-selected edge of the bracket 22 as an index for locating the shaft 33 the proper distance from the center of the ellipse to be drawn.

The operator next positions the centering pins 45 14 on the major axis and further positions the intermediate centering pin 14 at the center of the ellipse. Then with the point of the instrument 42 suitably engaged with the surface to be marked, the beam 11 is rotated completely around the standard 10 by steadyng the latter with one hand and moving the former through the medium of the handle 58, whereupon the instrument 42 describes the desired ellipse.

For example, Figure 2 diagrammatically shows successive positions of the ellipsograph as an ellipse 59 is described thereby. When the beam 11 is turned clockwise, the shaft 33 is also moved clockwise therewith in a circular path about the center of the ellipse. Simultaneously, the arm 34 is rotated in opposite counter-clockwise direction about the axis of the shaft 33 at the rate of two revolutions of said shaft 33 for each revolution of the beam 11 about the standard 10, and in passing through the upper left quadrant from the position designated by the letter A, thence through the positions B and C, and finally into the position D, the arm 34 rotates about the axis of shaft 33, that is, from a position at A paralleling the major axis X-X into a position at D paralleling the minor axis Y-Y, thus shifting angularly through an angle of 90° for the initial quadrant of the ellipse described, in consequence of which the instrument 42 shifts from the extremity of the major axis, which is disposed out 70 side of the circular path of the shaft 33, to the

extremity of the minor axis, which is disposed inside the circular path of the shaft 33, thereby describing the first quarter of the ellipse. It will be apparent that for each quarter turn of the beam 11 in clock-wise direction, the shaft 33 and its associated arm 34 will rotate a half turn in counter-clockwise direction, the net result being a 90 degree counter-clockwise angular displacement of the arm for each quadrant of the ellipse described by the scribing instrument. The 10 operation of the ellipsograph in each succeeding quadrant is similar, and, of course, the complete ellipse is drawn when the beam 11 is rotated one complete revolution in either direction about the standard 10 as its center.

It will be seen that whenever the rod 46 is disposed in coincidence with and parallel to the major or minor axis of the ellipse, the flat sides of the blades of the drawing pen 42 are disposed in tangential relation to the ellipse. This predetermined relation is maintained even in the intermediate positions of the ellipsograph, such as those designated by the letters B and C, by so shifting the bracket 23 on the beam 11 and securing it in position that the distance between the axes of the standard 10 and the shaft 43 is twice that between the axes of the standard 10 and the shaft 33. In this connection, it will be observed that while the ellipsograph is passing from one position to another, as from the position B to the position C, the angular position of the arm 34 relative to the rod 46 changes. For accommodating this angular change the effective length of the rod 46 is automatically changed as required by axial shifting movement thereof relative to the shaft 43 simultaneously as the latter oscillates about its own axis while it traverses a circular orbit about the center of the ellipse. It will be noted that the graduated scale on the beam 11 may be employed to locate the bracket 23 in any predetermined adjusted position upon the beam, a preselected edge of the bracket 23 serving in such case as the locating index for the bracket.

While the beam 11 has been shown and described as secured to the standard 10 through the medium of a separate plate bracket, it will be understood that the latter may be formed as an integral part of the beam 11 and that the entire beam may be stamped from a single piece of sheet material. In this connection, it will be observed that the four plate brackets respectively comprising the parts 22, 23, 28 and 29 each may be made in a single stamping.

While the marking element of the present invention has been shown and described as a pen having flat sides, it will be understood that the marking element may take other forms which are directional in character, e. g., a cutting blade, a glass-cutting wheel, a paint striping brush or a chisel-point pencil. In addition, while the flat sides of the scribing instrument have been shown and described as constantly disposed in tangential relation to the portion of the ellipse being drawn, it will be understood that by suitable shifting of the bracket 23 along the beam 11 into a position other than that above described for constant tangential disposition of the instrument 42 along the line of the ellipse, the point of the instrument may be caused to progressively assume different positions relative to the line of the ellipse being drawn to thereby provide special shading effects. Furthermore, while the drawing illustratively shows a drawing pen as disposed normal to the surface upon which the ellipse is 75

to be drawn, it will be understood that the arrangement may be such as to position the lower end portion of the scribing element, whatever its form might be, in any desired inclined relationship to such surface. For example, a drawing pen may be arranged to incline either forwardly or rearwardly relative to the direction of travel or a cutting blade or other instrument may be arranged to incline inwardly or outwardly of the line of the ellipse to cut correspondingly beveled edges.

Still further, while an ellipse having a major axis equal to twice the length of that of the minor axis is shown in Figure 2, it will be evident that 15 the inherent characteristics of the ellipsograph of the present invention permits its use in describing an ellipse the major and minor axes of which are of any desired ratio including any wherein the major axis is of a length more than 20 twice that of the minor axis. It will be apparent also that inasmuch as the rod 46 extends at all times exactly normal to the outline of the ellipse, it serves the useful purpose of readily determining 25 the true perpendicular or the true tangent to the ellipse at any desired point thereof.

It should be obvious, therefore, that the present invention is susceptible to various changes and modifications which may be made from time to time without departing from the principles thereof and it will be understood that it is intended to claim the invention broadly, as well as specifically, as indicated by the appended claims. In the foregoing specification and in the appended claims, the term "marking element" or "scribing element," wherever employed is intended to include not only the ruling pen 42 as illustrated but any other instrument such as a cutting blade, a striping brush or the like designed to delineate or cut out an ellipse of any desired form within the ellipse-describing capacity of the ellipsograph of the present invention.

What is claimed as new and useful is:

1. In an ellipsograph, a central centering element having an upright standard which is fixed against rotational movement, an elongated beam connected to said fixed standard for horizontal swinging movement thereabout, first and second brackets each selectively positionable along said elongated beam, a bevel gear fixed on said standard in permanent coaxial relation thereto, a driven bevel gear rotatably carried by said first bracket, intermediate bevel gear means including a shaft rotatably carried by said elongated beam 45 and a pair of bevel gears mounted on axially spaced portions of said shaft for rotation therewith, one of the gears of said pair being disposed in meshing relation with said fixed gear and the other gear of said pair being similarly associated 50 with said driven bevel gear and selectively positionable along said shaft with the first bracket, a radius arm adapted to be fixed with respect to the axis of said driven gear in a radially adjusted position less than the distance from the driven gear axis to the central standard, a scribing element mounted on said radius arm for rotation with respect thereto about an axis parallel to the axis of the driven gear, whereby said driven gear, radius arm and scribing element are revolvable as a unit with the beam about the axis of 55 said fixed standard and said scribing element is simultaneously revolvable about the axis of said driven gear, said scribing element constituting a flat member with a lower scribing edge, said radius arm and scribing element being carried 60

by the first bracket, a shaft parallel to said standard, means mounting said last-named shaft on the second bracket for free oscillation about the longitudinal axis of the shaft, and guiding means extending between said scribing element and said freely oscillatable shaft on said second bracket and operative to oscillate said element about its rotary axis to maintain its operative edge in constant tangential relation to the elliptical line of the ellipse as it is described by the ellipsograph, the effective length of said guiding means being shorter than the distance between the second bracket and the central standard and said guiding means being located entirely outside the elliptical area being described.

2. An ellipsograph as set forth in claim 1 wherein in the guiding means constitutes a rod, wherein one face of the flat scribing element is disposed outwardly with respect to the ellipse, wherein an end of the rod is rigidly fixed to said outwardly facing face and wherein said rod slidably engages the freely oscillatable shaft.

3. An ellipsograph as set forth in claim 1 wherein the flat scribing element is elongated and has a longitudinal axis parallel to the central standard.

5 4. An ellipsograph as set forth in claim 1, wherein the beam is provided with graduations forming a single scale extending longitudinally thereof, and wherein the movement of both the brackets on said beam is measurable by readings 10 on the scale.
